UNITED STATES PATENT OFFICE.

JOSEPH RYAN, OF ST. LOUIS, MISSOURI.

LUBRICATOR.

SPECIFICATION forming part of Letters Patent No. 363,684, dated May 24, 1887.

Application filed January 27, 1886. Serial No. 189,951. (No model.)

To all whom it may concern:

Be it known that I, JOSEPH RYAN, of the city of St. Louis, in the State of Missouri, have invented a certain new and useful Improvement in Lubricators, of which the following is a full, clear, and exact description, reference being had to the accompanying drawings, forming part of this specification, and in which—

10 Figure 1 is a side elevation of my improved lubricator, showing it applied to a compressor, part of the compressor being shown in section. Fig. 2 is an enlarged view of the oil-tanks, one of the tanks and its parts being shown 15 in side view and one in vertical section. Fig. 3 is a horizontal transverse section through one of the parts, taken on line 3 3, Fig. 2. Fig. 4 is an enlarged vertical section of one of the main condensers and its adjacent 20 parts. Fig. 5 is an enlarged vertical section of an auxiliary condenser. Fig. 6 is an enlarged vertical section of the sight-feed and its adjacent parts. Fig. 7 is a vertical section taken on line 7 7, Fig. 6. Fig. 8 illustrates a modified 25 form of the sight-feed, this being the form that is preferably used on the branch oil-pipes of the compressor. Fig. 9 represents the valve located between the compressor and sight-feed. Fig. 10 represents an enlarged vertical 30 section of the sight-feed, the auxiliary condenser, the parts connecting the condenser and sight-feed, and part of the steam-pipe.

My invention relates to a lubricator involving several novel features, hereinafter fully 35 described, and pointed out in the claims.

Referring to the drawings, A represents a steam-pipe leading to or from an engine, B.

C represents a compressor connected to and operated by the engine B in the usual manner.

40 C' represents the pipe connecting the valves of the opposite ends of the compressor, as usual.

As I claim nothing in the engine or in the compressor *per se*, it will be unnecessary to 45 describe them or their construction more particularly.

D represents an oil-tank for holding oil to lubricate the compressor C, and E represents a tank for holding oil to lubricate the engine 50 B. These tanks are located side by side, but have no such connection as will permit the mingling of the two kinds of oil, which is im-

portant, it being well known that black-oil will answer best the purpose of lubricating ammonia-gas compressors, and it also being 55 well known that engine-oil is the best for lubricating engines, therefore the tank D is filled with black-oil and the tank E with engine-oil. They may be filled through a funnel, F, supported on a short pipe, F', connecting the two 60 tanks, and provided with valves F', one on each side of the funnel. By opening either one of these valves a communication is made between the funnel and the tank on that side of the funnel. The construction of these tanks 65 is illustrated in Fig. 2. Each is made with an inner chamber, G⁹, surrounded by a jacket or chamber, G¹⁰, the feed-pipe F' communicating with the chamber G⁹, as shown. The object of this jacket or chamber G¹⁰ is to permit the 70 circulation of a warm medium around the oil to keep the oil in a liquid condition in cold weather or in cold rooms. This is preferably done by means of steam caused to enter the chamber G¹⁰ through a pipe, G¹², as shown in 75 Fig. 2, which connects with a pipe, G¹⁴, leading to the steam-pipe A. (See Fig. 1.) The water can be drawn from the tanks through an escape-pipe, H, provided with a valve, H'.

The oil from the tank D is conveyed to the 80 compressor C through a pipe, G, and branch pipes G', the latter being connected with the pipe G by a coupling, G², and are provided with valves G⁴, to regulate the feed of the oil. Each branch pipe is also provided with a sight- 85 feed, G³, and with check-valves G²⁰, (see Figs. 1 and 9,) so that in case of the sight-tubes being broken the escape of gas from the compressor will be shut off automatically.

I have shown one of the sight-feeds, Fig. 1, 90 arranged to feed downward—that is, the one on the left-hand side—and the other to feed upward, so that either arrangement may be used. In the latter case any gas from the compressor is prevented from coming in contact 95 with the metal that would be corroded by it, this being prevented by the water in the sight-feed, the metal part of which is made of brass, which would be affected by the gas if exposed to it.

The oil from the tank E is conveyed therefrom to lubricate the engine B through a pipe, H², sight-feed I, and the steam-pipe A. The passage of the oil from the tank is regulated

or may be shut off entirely by means of a valve, P, which is shown open in Fig. 2, a similar valve, P^d, being provided for the tank D. The construction of the sight-feed I is illustrated in Figs. 6, 7, 8, and 10, the end of the pipe H² where it is connected with said sight-feed being shown in Figs. 6 and 10. The lower end of the glass tube I' of the sight-feed is connected to a base piece, I², which in turn is connected by a short coupling, I³, with an L-shaped pipe, I⁴, to which is connected the end of the pipe H². This pipe I⁴ has a valve, I⁵, to shut off the flow of oil when the parts are to be disconnected. The short pipe I³ is connected to the base-piece I² by a stuffing-box, I⁶. The base-piece has a valve, I¹⁵, to regulate the flow of oil to the parts to be lubricated.

I⁷ represents the nipple of the feed-tube, which is secured to and supported by the base-piece I², between which latter and a coupling-piece, I¹⁰, the glass tube I' of the sight-feed is held and supported in the manner described in my copending application, Serial No. 149,354.

I⁸ represents the top piece of the sight-feed, which is connected with the steam-pipe A by means of a short pipe, I⁹, and is connected with the coupling-piece I¹⁰ by means of a short section I¹⁴, the meeting ends of the said section I¹⁴ and coupling-piece I¹⁰ being formed as shown in Fig. 10 and clamped together by a union or collar, I¹². This top piece also communicates at top with a condensing-chamber, I¹⁵. By this construction steam entering through pipe I⁹ is received in the condenser, the water of condensation flowing down through top piece, I⁸, and filling the sight-feed tube I', whereby the oil rises through the water as it passes to the parts to be lubricated.

The passage of the oil from the sight-feed into the steam-pipe A, or of the steam in the reverse direction, may be regulated or closed by a valve, I¹³. A connection similar to that shown at I¹¹ may be made between the pipe I³ and the base-piece I², as shown in Figs. 6 and 10.

It frequently happens in these lubricators that the sight-tube becomes coated on the inside with impurities from the oil, so that it is difficult to see whether the feed of the oil is going on or not.

To afford a convenient means for washing or cleaning the inside of the sight-feed tube, I have devised the following arrangement: In Figs. 1, 5, and 10 an auxiliary condenser, J, is shown connected by means of a globe or other valve, J', and a short pipe, J², to the steam-pipe A, and consisting of a globe or chamber, J, with a central tube, J³, for the passage of the steam, which condenses into water and passes from the chamber J through a pipe, J⁴, to a valve, J⁵, whence it passes through a pipe, J⁶, to the base-piece I² of the sight-feed I. By closing the valve J' the steam from the pipe A may be shut off, and by closing the valve J⁵ the water may be shut off from passing through the sight-feed tube. In addition to

the water acting to wash the glass, it also acts as a vehicle to carry the oil through the sight-feed tube into the steam-pipe.

J⁷ represents a check-valve located in the pipe J⁶, which will close as soon as the pressure in the pipe J⁴ and in the sight-feed tube become equal, and remain closed while the pressure in the said tube is in excess of that in the pipe J⁴, thus preventing any return or back-flow of the water through these parts, which would interfere materially with the continuous feed of the oil. This backflow would also result in soiling the sight-tube, as the passage of the water would then be downward through the sight-feed tube; but in case of any back-pressure, whether it be due to the pulsation of the engine or other causes, this valve will close, thereby preventing a backflow of the oil and water. The base-piece I² has an opening or duct, J⁸, for the passage of the water from the pipe J⁶ (see Fig. 7) to the sight-feed tube I, said duct communicating with the lower end of said tube and at the base of the nozzle I⁷.

In case it should be desired at any time to drain the water from the sight-feed tube, it can be done by closing the valves J⁵ and I¹⁵ and opening a valve, J⁹, at the bottom of the base-piece I². This valve is shown closed in Fig. 10 and open in Fig. 6, and when these valves are in these positions steam may be blown through the sight-feed tube from the pipe A to clean out the parts.

In the steam-pipe G¹⁴, which furnishes heat for the oil-tanks E D, as stated, I place a condenser, M, as shown in Fig. 1, the construction of which is illustrated in Fig. 4. This condenser is connected to the pipe G¹⁴ by means of a coupling having a valve, M', which can be used to regulate or cut off the flow of steam. The water of condensation passes through a perforated cage, N, at the bottom of the condenser, the pipe N', and branch pipes N² to the respective tanks E and D. The branch pipes are provided with valves N³ and connect with the tanks through means of a head-piece, O, having ports O' for the flow of water, and provided with valves O². The water is carried to the bottom of the oil-tanks by means of inclosed pipes O³, connecting with the ports O', and as it enters it displaces the oil through the pipes G and H², as described.

In case it should be desirous to close off the flow of water into the tanks without stopping the passage through the pipes N' and N², it may be done by shifting the valves O² from the position shown in Fig. 2, when they would bear against seats O⁴, closing the ports O' and opening the ports O⁵ into the oil-pipes H² and G. Then by closing the valves P (located in ports P' formed in the head-pieces O to make a communication between the oil-tanks and the pipes H² and G) a circulation of water may thus be had through the oil-pipes for the purpose of cleaning them. This circulation

may be carried on through the night, or when the machinery is at rest, while there is steam in the steam-pipes, so that the only thing that is necessary to do in order to clean the pipes is to shut off the flow of oil and reverse the valves O^2 .

This invention is very closely allied to those described in my contemporaneous applications, Serial No. 149,354 and No. 189,950, filed on the 6th day of October, 1884, and on the 27th day of January, 1886, respectively, only such novel features being herein claimed as are not claimed in one or the other of said applications.

15 I claim as my invention—

1. The combination, in a lubricator, of the oil-tank D, pipe G, having branches G', connecting said tank with the parts to be lubricated, a sight-feed, G³, located in each of said branches, and automatic valve G²⁰, located in each of said branches between the sight-feed and part to be lubricated, substantially as set forth.

2. In a lubricator, the combination, with the oil-tank and pipe G, having branches G', connecting it with the parts to be lubricated, of a sight-feed, G³, located in each of said branches, the automatic valves G²⁰, located in said branches between the sight-feed and the part to be lubricated, and the screw-valves G⁴, located between said sight-feed and the intersection of the said branches, substantially as set forth.

3. The combination, with the independent oil-tanks D E, independent pipes for conveying oil therefrom for lubricating the compressor C and engine B, respectively, and a water-supply, M, common to both, of a pipe, N', having branches N², communicating with said water-supply and the respective tanks, substantially as set forth.

4. The combination of the oil-tank D, pipe connecting said tank with the part to be lubricated, head-piece O, located on the tank, having ports P' and O', with which the oil-tank communicates, condenser M, connected to the steam-pipe A, and pipe forming communication between the condenser and oil-tank through port O', substantially as set forth.

5. In combination with the oil-tank having the head-piece O, provided with ports O' and P', communicating with said tank and with each other, oil-pipe communicating with the port P', valve P for closing said port, water-pipe N', communicating with port O', and valve O², controlling said port and also the communication between the two ports O' and P', whereby the flow of water from the condenser may be allowed to pass into the oil-tank, or

closed therefrom and caused to flow through 60 the oil-pipe, substantially as set forth.

6. The combination, in a lubricator, of a steam-pipe, A, sight-feed I, oil-tank E, means for forcing the oil therefrom into said sight-feed, condenser J, having communication with 65 the pipe A, pipe J⁴, forming communication between the condenser and sight-feed, and valve J⁵, located in said pipe between the sight-feed and condenser J, substantially as set forth.

7. The combination, with the steam-pipe A and condenser J, with which it communicates, of sight-feed I, a pipe, I⁹, through which the latter communicates with the steam-pipe A, the pipe J⁴ J⁶, connecting the sight-feed and 75 condenser, and an automatic valve, J⁷, for preventing back flow through said sight-feed, substantially as set forth.

8. The combination of the steam-pipe A, sight-feed I, base-piece I², connected to the 80 sight-feed and provided with ports J⁸, pipe J² J⁴ J⁶, forming connection between the steam-pipe and the ports J⁸ in the base-piece, and provided with valves J⁵ and J⁷, and a condenser, J, located in said pipe, substantially as set 85 forth.

9. The combination, in a lubricator, of the steam-pipe A, sight-feed I, base-piece I², connected to the sight-feed and having port or ports J⁸, pipe J² J⁴ J⁶, forming connection between the steam-pipe and the ports J⁸ in the 90 base-piece, and a check-valve, J⁷, located in said pipe, for the purpose set forth.

10. In a lubricator, the combination of the steam-pipe A, the sight-feed I, the pipe I⁹, 95 communicating at one end with the steam-pipe and at the other end with the upper end of the sight-feed, the condenser I¹⁵, also communicating with the upper end of the sight-feed tube, the base-piece I², having duct communicating 100 with the sight-feed at bottom, the oil-supply pipe H², communicating with said base-piece, the valve I⁶, for controlling the flow of oil through the pipe H², and the valve I¹⁵, for regulating the feeding of oil to the sight-tube, substantially as set forth.

11. In a lubricator, the combination, with an oil-tank, E, a water-supply, M, and a pipe, N', leading from the water-supply to the oil-tank, of a sight-feed, I, a pipe, H², connecting 110 the oil-tank and sight-feed, a condensing-chamber, J, and a pipe leading from the condensing-chamber to the bottom of the sight-feed tube, substantially as and for the purpose set forth.

JOSEPH RYAN.
